[57] CLAIM

The ornamental design for a frozen confection and a package therefor, as shown and described.

DESCRIPTION

FIG. 1 is a front elevational view of the frozen confection and a package therefor shown in unopened condition;

FIG. 2 is a front elevational view of the FIG. 1; the opposite side being identical except for the tag;

FIG. 3 is a side elevational view of FIG. 1; the opposite side being a mirror image;

FIG. 4 is a top plan view of the FIG. 1;

FIG. 5 is a bottom plan view of FIG. 1;

FIG. 6 is a perspective view of the frozen confection and a package therefor, with the frozen confection shown separately for clarity of illustration;

FIG. 7 is a front elevational view of FIG. 6; the opposite side being identical;

FIG. 8 is a side elevational view of FIG. 6; the opposite side being identical;

FIG. 9 is a top plan view of FIG. 6; and,

FIG. 10 is a bottom plan view of FIG. 6.
